UNITED STATES PATENT OFFICE.

HOWARD EARL HOOVER, OF CHICAGO, ILLINOIS, ASSIGNOR TO THE HOOVER SUCTION SWEEPER COMPANY, OF NEW BERLIN, OHIO, A CORPORATION OF OHIO.

SUCTION-SWEEPER.

1,247,837.

Specification of Letters Patent. Patented Nov. 27, 1917.

Original application filed December 8, 1916, Serial No. 135,731. Divided and this application filed March 8, 1917. Serial No. 153,507.

to all whom it may concern:

Be it known that I, HOWARD EARL HOOVER, a citizen of the United States, residing at Chicago, in the county of Cook and state of Illinois, have invented a certain new and useful Improvement in Suction-sweepers, of which the following is a specification, being a divisional application of applicant's copending application Serial No. 135,731.

My application relates generally to improvements in suction sweepers, and relates more particularly to certain operatively important details which coöperate to render my device satisfactory and effective.

One object of my invention is to provide an arrangement which will effectually prevent entangling within the suction nozzle of the fringes and edges of carpets, rugs and the like, while permitting the introduction into the nozzle of paper, matches and scraps. Other objects will appear from time to time in the specification.

The invention is illustrated more or less diagrammatically in the accompanying drawing, wherein—

Figure 1 is a section through a portion of suction sweeper showing the invention which forms the subject matter of this application;

Fig. 2 is a bottom plan view with parts taken away and parts omitted of a suction sweeper embodying my invention.

Like parts are indicated by like letters in both figures.

A is a suction nozzle partially supported by means of rollers A¹ in such wise that it is located slightly above the floor or surface to be cleaned. A² is a suction fan driven by motor A³ which draws air in through the nozzle and discharges it into a suitable receptacle not here shown. A⁴ is a brush in the nozzle driven by means of a belt A⁵ from the fan shaft A⁶. It will be noted that the bristles of the brush extend a short distance below the plane of the nozzle, so that when the suction draws the carpet or other material to be cleaned up against the nozzle, the brush will be able to strike it, brush it, and vibrate it.

B is a cross bar pivotally supported by the bracket plates B¹ within the nozzle. Extending rearwardly from this cross bar are series of guard fingers B². These fingers

where they leave the bar, are bent down for 55 a short distance until they reach the plane of the nozzle. They are then bent back in that plane and extend substantially across the nozzle. However, just before they reach the rear wall of the nozzle, they are bent 60 upwardly, and again bent rearwardly. The result is that there is a space between the rear ends of these guard fingers and the rear edge or wall of the nozzle through which matches, paper, scraps and the like can pass 65 up between the edge of the nozzle and the guard fingers.

The inwardly projecting ends of the fingers are so placed that the loops or edges or fringes of rugs, carpets and the like, cannot catch on the ends of the fingers when the motion of the device is reversed.

It is understood that there is always a great deal of vibration in a machine such as this caused by the striking of the brush 75 upon the fingers and also upon the carpet from contact with which the fingers lie, and an additional reason why it is necessary to have the ends of these fingers free and out of contact with the rear edge of the nozzle 80 is that otherwise they would strike against this nozzle and vibrate and cause a great deal of unnecessary noise, to say nothing of the fact that a close contact prevents the drawing in of parts or objects larger than 85 the space between adjacent fingers.

The fingers themselves are, of course, necessary in order to prevent the carpet being drawn up too far into the nozzle against the brush and to prevent it being wound 90 about the brush, and also to hold the carpet in a relatively flat plane, that is to say, the plane of the nozzle. In order that the brush may not be too greatly interfered with as it rotates, the carpet is not permitted to 95 bow up too far into the nozzle against the brush, as otherwise the power necessary to drive the brush would be too great, and the wear upon both the carpet and brush would be excessive.

I wish it to be understood that my drawings are to be taken as diagrammatic for some of the parts illustrated can be varied in size, shape and arrangement and some may be substituted without departing from 105 the spirit of my invention.

The use and operation of my invention are as follows:—

The suction sweeper when in operation, is moved back and forth along the floor in the usual way, being supported by the rollers. The suction induced by the fan draws the rug or other floor covering up against the face of the nozzle or the fingers so that the cover may be struck or swept and vibrated by the brush which rapidly rotates. The guard fingers across the nozzle prevent the rug from being drawn inside. Since the guard fingers extend back into the housing without actually touching its inner surface, paper, scraps or pieces longer than the space between the fingers can be drawn into the apparatus by the blast of air.

By this arrangement of the finger ends they are so located that the loops found in the fringe or edge of rugs or carpets will not become entangled with or engaged on the ends of the fingers when the motion of the machine is reversed. This result is due to the fact that the ends of the fingers project a considerable distance inside of the chamber or housing back of the nozzle. Thus by arranging the fingers as shown, I permit the free movement of large scraps between the fingers and the housing entrance while at the same time preventing the entanglement of fringe loops with the ends of the fingers.

It will be observed that the fingers are so arranged that they extend across the suction

opening into the suction chamber and beyond or behind the rear lip of the suction opening, that is to say, they extend in that part of the housing which is located behind the rear lip of the suction opening but are not in contact with the housing at any place except at the front end where they are fastened.

I claim:

1. In a suction sweeper the combination of a housing inclosing a suction chamber and having a suction opening with a series of fingers extending across the opening and projecting into the suction chamber but out of contact with the rear lip of the suction opening.

2. In a suction sweeper the combination of a housing inclosing a suction chamber and having a suction opening with a series of fingers extending across the opening, said fingers extending upwardly and rearwardly into the suction chamber but out of contact with the rear lip of the suction opening.

In testimony whereof, I affix my signature in the presence of two witnesses this 26th day of February 1917.

HOWARD EARL HOOVER.
